Patented Mar. 29, 1960

187,540

SET OF CHESSMEN

Joseph C. Sparkman, Geneva, Ill.

Application October 7, 1959, Serial No. 57,850

Term of patent 14 years

(Cl. D34—5)

Fig. 1 is a perspective view of a set of chessmen, embodying my new design;

Fig. 2 is an elevational view thereof; and

Fig. 3 is a top plan view thereof.

I claim:

The ornamental design for a set of chessmen, substantially as shown.
